SKI POLE RING

Alexander C. H. Weiss, Chicago, Ill.

Application February 28, 1951, Serial No. 14,340

Term of patent 14 years

(Cl. D34—14)

To all whom it may concern:

The invention described herein, if patented, may be manufactured and used by or for the Government for governmental purposes without the payment to me of any royalty thereon.

Be it known that I, Alexander C. H. Weiss, a citizen of the United States of America, residing at Chicago, in the county of Cook and State of Illinois, have invented a new, original, and ornamental Design for a Ski Pole Ring, of which the following is a specification, reference being had to the accompanying drawings, forming a part thereof.

Fig. 1 is a top plan view of a ski pole ring, showing my new design;

Fig. 2 is a diametrical cross section taken on line 2—2 of Fig. 1; and

Fig. 3 is a side elevational view thereof.

I claim:

The ornamental design for a ski pole ring, as shown.

ALEXANDER C. H. WEISS.
